UNITED STATES PATENT OFFICE.

SAMUEL W. RUSHMORE, OF PLAINFIELD, NEW JERSEY.

INTERNAL-COMBUSTION ENGINE.

Application filed January 30, 1928. Serial No. 250,424.

My present invention concerns internal combustion engines of the type set forth in my companion applications resulting in Patents Nos. 1,658,463 and 1,658,464. As explained in said patents, the improvements apply particularly to engines of the prior art, wherein high compression is known to be highly desirable for efficiency and economy of fuel consumption, but the nature of the combustible fuel and the conditions of its burning within the engine are such that the desired high compression is substantially limited by reason of tendency of the combustible mixture to detonate instead of burn in an orderly manner.

A specifically important feature of the inventions set forth in said companion cases is their applicability to engines of the so-called T-head type, wherein the intake manifold and valves are on one side of the engine and the exhaust manifold and valves on the other side of the engine. While this type of engine is highly desirable because it permits the use of large valves and for other reasons, it has been found to afford conditions particularly favorable for detonation and hence least favorable for high compression.

Both said companion cases contemplate splitting up the compression space of each cylinder into a plurality of chambers that are virtually separated at the instant of ignition, preferably employing two spark plugs for each cylinder, one in each of its compression chambers. In No. 1,658,463, the separate chambers are preferably located symmetrically on opposite sides of the cylinder, each overlapping a relatively small area of the piston, on opposite sides thereof. With this arrangement and with the explosion substantially simultaneous in each chamber, the pressures initially applied to the head of the piston will be approximately equal on opposite sides of the line of thrust.

In No. 1,658,464, most of the compression space of each cylinder is localized adjacent the inlet valve, leaving only a small compression space adjacent the exhaust valve, but as in the other case, the head is shaped so that these two chambers are virtually separated at the instant of ignition.

While, broadly considered, my present invention is applicable in either of these cases, I prefer to combine it with the features of the latter case, No. 1,658,464. In this form the exit from the cylinder to the exhaust

valve may be of substantially reduced cross-section and may even show very substantial resistance to escape of the exhaust. Very considerable resistance is of relatively small effect because the major part of scavenging of the cylinder occurs as soon as the exhaust valve opens and releases the high pressure part of the exhaust gas. The remainder of the scavenging during the exhaust stroke requires relatively low velocity outflow. Consequently, material throttling or resistance of the exhaust outlet will cause only a slight effect upon the brake horse power of the engine, and this is more than compensated for by the effect of such throttling resistance, in keeping the combustible charge away from the hot exhaust valve, thus making it possible to raise the compression to a very high figure without any danger of detonation.

As detonation is caused and completed only at the instant the piston is at the top of its stroke, no moving parts other than the piston are necessary for thus separating the compression spaces. In both of my prior cases this is accomplished by forming the cylinder head and the head of the piston so as to afford a zone of minimum clearance over all the central part of the piston head area, said zone being preferably made as wide as practicable at the ends adjacent the periphery.

My present invention concerns an improvement which consists in providing for the minimum clearance zone, a stepped or baffle zone in the nature of interfitting elevated and depressed surfaces on the piston head and cylinder head. Preferably substantial parallelism is maintained for the stepped construction of my present invention, as for the plane construction elected for illustration in said prior cases.

I have determined by actual experiment, that even with the baffle arrangement, the permissible clearance between surfaces may be reduced to a very few thousandths of an inch without danger that carbon deposits will cause the piston head to pound the cylinder head. If the carbon were suddenly introduced, the pounding naturally would be severe, but the so-called carbon is initially a soft, gummy deposit, consisting mainly of silica from the road dust with some carbon and oil. The deposit is gradual and, being soft and tarry, is simple squeezed along and ejected before it has time to form

a solid. Consequently, any carbon deposits that can form merely serve the useful function of a self gauging sealing between the parallel surfaces. The deposit is therefore a benefit instead of a danger, because thereby the clearance space between these parallel surfaces, automatically becomes very thin and it is so extended that flame initiated in the compression space adjacent the inlet valve, will become chilled and incapable of cutting a passage through the carbon to permit passage of a detonating wave over to the exhaust valve passage, even in case the latter should contain an explosive charge.

15 The above and other features of my invention will be more fully understood from the following description in connection with the accompanying drawings, in which

Fig. 1 is a vertical axial section transversely of an internal combustion engine of the T-head type, having my invention embodied therein, the section being on the line 1—1, Fig. 2;

Fig. 2 is a top plan view of the cylinders and valves with the cylinder head removed.

In these drawings, the parts of the engine necessary to an understanding of my present invention are shown as comprising the cylinder 1, provided with a water-jacket 2, formed with an intake 5, controlled by intake valve 6, an exhaust 3 controlled by an exhaust valve 4, a piston 7 in the cylinder and, in operative relation to the above parts, a cylinder head 8, provided with a water-jacket 9 and having mounted therein spark plugs 10, 11.

As shown in Fig. 1, in the position of the piston 7 on dead center at the upper end of the compression stroke, it has all the central area of its upper face 7^a closely confronted by a broad lower surface 8^a of the cylinder head 8. The clearance between 7^a and 8^a may be reduced to approximately the minimum practically permissible by conditions of ordinary operation. The important feature is that this broad central zone of minimum clearance is in a different plane from the piston surfaces 8^b and 8^c that are adjacent the inlet and exhaust chambers respectively, so that one of the elements, preferably the piston head, has this zone projecting into a recess in the other. This arrangement affords transverse ribs on the cylinder head extending entirely across the piston head, one, 8^a adjacent the inlet 14 and the other 8^b adjacent the exhaust. By this arrangement, a pre-ignition or detonation wave would have to travel a greater total distance than in my prior arrangement, besides encountering four corner turns giving four baffling, cooling impacts, progressing from one chamber to the other across the piston head. This makes certain that no such wave can get across, even though the minimum clearance be considerable. In this

arrangement, the four confronting planes of the interfitting parts are preferably parallel and all of minimum working clearance.

The compression space is afforded mainly by the chamber 14, which is an enlarged inlet valve chamber and may have its discharge outlet 14^a leading into the cylinder, as large and of as low resistance as may be desired. On the other hand, the exhaust valve chamber 13 is of small volume and affords a small somewhat throttled outlet from the cylinder.

As indicated in dot and dash lines, Fig. 2, the chambers 13 and 14 extend toward each other so as to partially overlap the head of the piston 7. The area of the overlap of each chamber may vary considerably from that shown as may also the volumes of the chambers, but always there is a wide area zone of the interfitting small clearance surfaces between them, when the piston is in the position shown. In the drawing, the largest overlap, that of inlet valve chamber 14, is less than one-third of the diameter and less than one-sixth of the area of the piston head.

It results from the above relation of parts that the two chambers 13, 14, constitute a single compression space in so far as concerns density and degree of compression during the compression stroke, but the explosive mixture goes mainly into 14 and, so far as concerns burning of the charge and particularly as concerns propagation of a detonating wave, the main compression space 14 is effectively separated from the red hot exhaust valve 4, by the piston when at the upper limit of its stroke.

For instance, assuming a compression ratio of, say, 5 to 1, the combustible charge in the intake chamber will be 20 parts exhaust gas and eighty parts fresh mixture, but the exhaust chamber, being an isolated pocket and removed from the stream of incoming charge, will contain nothing but burnt gas until the beginning of the compression stroke and at the end of compression $\frac{4}{5}$ of the space will be $\frac{1}{5}$ exhaust and $\frac{4}{5}$ of the space all exhaust, making approximately thirty-six parts of exhaust gas to sixty-four parts of fresh charge. As there can be very little turbulence in my elongated and restricted exhaust chamber, it is probable that most of the exhaust is crowded to the farthest end, and there, where the exhaust valve will be the hottest, there is nothing but exhaust gas. Therefore, even if a thin sheet of flame should enter the exhaust chamber, the combustion could not by any chance approach detonating violence.

Conversely, the gases in 13 are cut off from 14 and the separation is such that a separate spark plug for 13 and 14 may be desirable for causing synchronized sparks in the two chambers to initiate combustion in 13

both parts of the charge, if the proportions and conditions of operation are such that 13 will contain a burnable charge. In any event, actual experience shows that by my 5 invention there is no possibility of backfiring or detonation, but only increasing efficiency and smooth running with compression ratios of 5½ to 1 and 6 to 1, ratios that are unheard of in present-day automobile 10 engines of any other type.

By my above described invention, I am enabled to so increase the compression that with the larger valves permitted by the T-type construction, the cost of the desirable 15 T-head design, for a given rated horse power, may be considerably lower than that of the cheaper L-head design while there may be also an appreciable saving in weight.

I claim:

1. An internal combustion engine, of the high-compression, T-head type, having a valved inlet passage for intake of an unignited charge located on one side of said head and a valved exhaust outlet chamber located in the opposite side; said engine including also a cylinder, piston and cylinder head arranged to afford a plurality of compression chambers, separated by areas of small clearance, said areas including transverse barrier elements extending entirely across the cylinder head and the piston adapted to overlap and baffle intercommunication between said chambers when the piston is at the upper end of the compression 30 stroke, one of said compression chambers including the inlet on one side of the barrier and the other including the exhaust outlet on the other side of the barrier.

2. An internal combustion engine, of the high-compression, T-head type, having a valved inlet passage for intake of an unignited charge located on one side of said head and a valved exhaust outlet chamber located in the opposite side; said engine including also a cylinder, piston and cylinder head arranged to afford a plurality of compression chambers, separated by areas of small clearance, said areas including transverse barrier elements extending entirely across the cylinder head and the piston adapted to overlap and baffle intercommunication between said chambers when the piston is at the upper end of the compression stroke, one of said compression chambers including the inlet on one side of the barrier and the other including the exhaust outlet on the other side of the barrier, in combination with a spark-plug in operative relation to said inlet chamber.

3. An internal combustion engine, of the high-compression, T-head type, having a valved inlet passage for intake of an unignited charge located on one side of said head and a valved exhaust outlet chamber located in the opposite side; said engine

including also a cylinder, piston and cylinder head arranged to afford a plurality of compression chambers, separated by areas of small clearance, said areas including transverse barrier elements extending entirely 70 across the cylinder head and the piston adapted to overlap and baffle intercommunication between said chambers when the piston is at the upper end of the compression stroke, one of said compression chambers 75 including the inlet on one side of the barrier and the other including the exhaust outlet on the other side of the barrier, in combination with spark plugs for each of said chambers.

4. An internal combustion engine, of the high-compression, T-head type, having a valved inlet passage for intake of an unignited charge located on one side of said head and a valved exhaust outlet chamber 80 located in the opposite side; said engine including also a cylinder, piston and cylinder head arranged to afford a plurality of compression chambers, separated by transverse barrier elements affording areas of small 85 clearance extending entirely across the cylinder head and the piston and interfitting when the piston is at the upper end of the compression stroke, one of said compression chambers including the inlet and the other 90 including the exhaust outlet, the chamber that includes the inlet being of large volume to afford most of the compression space, while the one including the exhaust outlet is relatively small and has communication with the cylinder space through an 95 exhaust outlet passage that is smaller than the inlet passage.

5. An internal combustion engine, of the high-compression type, having a valved inlet passage for intake of an unignited charge located on one side of said head and a valved exhaust outlet chamber located in the opposite side; said engine including also a cylinder, piston and cylinder head 100 arranged to afford a plurality of compression chambers, separated by transverse barrier elements affording areas of small clearance extending entirely across the cylinder head and the piston and interfitting when 105 the piston is at the upper end of the compression stroke, one of said compression chambers including the inlet and the other including the exhaust outlet, the chamber that includes the inlet being of large volume to afford most of the compression space, while the one including the exhaust outlet 110 is relatively small and has communication with the cylinder space through an exhaust outlet passage that is smaller than the inlet passage.

6. An internal combustion engine, of the high-compression type, having a valved in-

- let passage for intake of an unignited charge located on one side of said head and a valved exhaust outlet chamber located in the opposite side; said engine including also
- 5 a cylinder, piston and cylinder head arranged to afford a plurality of compression chambers, separated by transverse barrier elements affording areas of small clearance extending entirely across the cylinder
- 10 head and the piston and interfitting when the piston is at the upper end of the compression stroke, one of said compression chambers including the inlet and the other including the exhaust outlet, the chamber
- 15 that includes the inlet being of large volume to afford most of the compression space, while the one including the exhaust outlet is relatively small and has communication with the cylinder space through an
- 20 exhaust outlet that is smaller than the inlet, in combination with spark plugs for each of said chambers.
7. An internal combustion engine including cylinder, head and piston of diameter, stroke and clearance affording high compression, and having inlet and exhaust valves in separate inlet and exhaust chambers respectively located on opposite sides of the cylinder, whereby the exhaust valve is remote
- 25 from and is not cooled by the intake charge; said valve chambers being adapted to afford two compression spaces that are separated from each other by an area of small working clearance between cooperating surfaces
- 30 in the cylinder head and the piston respectively, when the piston completes its compression stroke, the cooperating surfaces including a transversely extending projection and a recess into which the projection fits, one being on the piston head and the other on the cylinder head.
8. An internal combustion engine including cylinder, head and piston of diameter, stroke and clearance affording high compression, and having inlet and exhaust valves in separate inlet and exhaust chambers respectively located on opposite sides of the cylinder, whereby the exhaust valve is remote from and is not cooled by the intake
- 45 charge; said valve chambers being adapted to afford two compression spaces that are separated from each other by an area of small working clearance between cooperating surfaces in the cylinder head and the
- piston respectively, when the piston completes its compression stroke, the cooperating surfaces including a transversely extending projection and a recess into which the projection fits, the projection being on the piston head and the recess being in registry therewith in the surface of the cylinder head.
9. An internal combustion engine including cylinder, head and piston of diameter, stroke and clearance affording high compression, and having inlet and exhaust valves in separate inlet and exhaust chambers respectively located on opposite sides of the cylinder, whereby the exhaust valve is remote from and is not cooled by the intake charge; said valve chambers being adapted to afford two compression spaces that are separated from each other by an area of small working clearance between cooperating surfaces in the cylinder head and the piston respectively, when the piston completes its compression stroke, the cooperating surfaces including a transversely extending projection and a recess into which the projection fits, one being on the piston head and the other on the cylinder head, in combination with a spark plug in operative relation to said inlet chamber.
10. An internal combustion engine including cylinder, head and piston of diameter, stroke and clearance affording high compression, and having inlet and exhaust valves in separate inlet and exhaust chambers respectively located on opposite sides of the cylinder, whereby the exhaust valve is remote from and is not cooled by the intake charge; said valve chambers being adapted to afford two compression spaces that are separated from each other by an area of small working clearance between cooperating surfaces in the cylinder head and the piston respectively, when the piston completes its compression stroke, the cooperating surfaces including a transversely extending projection and a recess into which the projection fits, one being on the piston head and the other on the cylinder head, in combination with spark plugs for each of said chambers.

Signed at Miami in the county of Dade and State of Florida this 24th day of January, A. D. 1928.

SAMUEL W. RUSHMORE.
